UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,070,141.

Specification of Letters Patent. Patented Aug. 12, 1913.

Application filed May 20, 1910. Serial No. 562,369.

To all whom it may concern:

Be it known that I, ALFRED G. F. KUROWSKI, a citizen of the United States, residing in borough of Brooklyn, city of New York, in the county of Kings and State of New York, have invented certain new and useful Improvements in Type-Writing Machines, of which the following is a specification.

This invention relates to web coiling devices applicable to typewriting machines wherein it is desired to maintain the printed web intact after it is fed from the platen.

In my co-pending application filed December 20, 1909, Serial No. 534,070, on which this invention is an improvement, several webs are fed together around the platen, the bills forming one web being torn off one by one to accompany the purchases, while the copy web is carried rearwardly to a spool or reel on which it is coiled.

One object of this invention is to improve the manner of coiling the fragile web, and to avoid injury thereto, to which end I lead the web through a guide which is automatically adjusted by causing one end thereof to press against or ride upon the winding roll, whereby the incoming web is straightened prior to coiling on the roll; and as the diameter of the roll increases, the web is directed or guided to the circumference thereof, without liability of kinking or bending. Advantage is also taken of the pressure of the adjustable guide against the roll to aid the web in coiling snugly, and also to constitute a brake to prevent the web from uncoiling accidentally.

Another object is to enable the leading end of the web to be easily and quickly fastened to the spool or reel, and in such manner that the coiled web may be easily removed.

This is accomplished by providing the spindle of the spool with a clamp or catch, by which one end of the web is secured, said spool having a removable head to allow the coiled web to be slid off endwise from the spindle, the leading end of the web sliding easily from beneath the clamp as the coiled web is slid off.

In the accompanying drawings, Figure 1 is a perspective view, partly broken away, illustrating the invention. Fig. 2 is a cross-section, showing the invention used in connection with an Underwood writing machine. Fig. 3 is a sectional view through

the spool and guide, dotted lines indicating the adjustability of the guide as the coil of the web increases in diameter. Fig. 4 is a detail view of the spool, the coiled web being shown in dotted lines. Fig. 5 is a perspective view of the leading end of the web, folded to facilitate its attachment to the winding spool. Fig. 6 is a detail perspective view of the removable head and a portion of the spindle, disassembled.

Paper rolls 1 and 2 are mounted on shafts 3 and 4, the webs 5 and 6 being led from the rolls over the rounded head 7 of the paper shelf 8 of an Underwood writing machine, thence passing around the platen 9 (against which they are held by front and rear pressure rolls 10 and 11), and upwardly in front of the platen printing point. The leading ends of the webs may be folded as shown at 24 (Fig. 5), before introduction between the platen and the pressure rolls. In the present instance, the web 5, leading from the paper roll 1, may comprise sales slips arranged in series, which are torn off successively as they are printed upon, to accompany the purchases. The web 6 constitutes a duplicate record, to be preserved, it being fed backwardly from the platen 9, and wound upon a spool or reel 18, 19, 20, from which the coiled web may be removed from time to time. The shafts 3, 4, supporting the paper rolls, are mounted in a casing 12, relatively to which the platen 9 travels back and forth, said casing being closed by a cover 13 hinged at 14. The spool or reel 18, 19, 20, on which the web 6 is wound, may be journaled in the bracket arms 15, secured to the cover. The web 6 is fed down the sloping cover or table 13 and between two parallel confining rods 16 extending between the arms 15, which rods not only coöperate with the bracket arms 15 to direct the feed of the web, but also, by reason of their elevation above the surface of the cover 13, hold a part of the web off the cover (Fig. 2), thereby avoiding the necessity of subjecting the weak web to strain or wear by reason of its frictional engagement with the cover during the back and forth travel of the platen 9.

To eliminate tension on the reach 6^a of the web between the platen and spool, owing to such relative movement between the platen and the spool or reel, the web is allowed to feed off the lower end of the

sloping cover 13 to form a loose bight 17 (indicated in Fig. 2) before being led to the spool. Said spool comprises a spindle 18 journaled in the bracket arms 15 and having heads 19, 20, between which the web is coiled. The spool is rotated by a crank 21, spring latches 22, pivoted at 23 to the arms 15, holding the spindle in place.

The leading end 24 of the web is easily 10 and quickly fastened to the spool by slightly raising a springy clamping finger or catch 25 seated in a groove 26 extending about longitudinally of the spindle 18, between which finger and spindle, the leading end is 15 inserted, the tension of the clamp crimping the paper into the groove. The clamping finger extends partway only across the spool, one end of the finger being fixed, and the opposite end being free; and the spindle has 20 a finger recess 27 to enable the clamping finger 25 to be grasped and raised. By turning the crank, the spool is rotated to wind the web thereon.

To avoid or minimize the liability of the 25 web being caused to snarl and wind unevenly on the spool, or becoming split on the edges, or torn across, the web is led up from the loose bight 17 over a supporting and guiding plate 28 swiveled or hinged on a rod 30 carried by branch arms 30 extending from the bracket arms 15, said plate having lips 31 turned over along its side edges to overlie the plate and form ways in which the side edges of the web 6 slide, whereby the 35 web is straightened out and guided to the spool. The introductory ends of the ways are outwardly flared, as at 32, to prevent injury to the web as it is drawn onto the guide, and to permit the web to be quickly coiled on 40 the spool from time to time by turning the handle 21. The opposite end of the plate is extended, as at 33, to form a follower, pressed against the circumference of the roll on the spindle by spring 34; and the web is 45 led between the follower 33 and the roll in winding thereon, whereby, as the diameter of the roll varies, in winding, the guide 28 will be rocked, so as to direct the web automatically to the circumference of the roll 50 (Fig. 3). The follower 33, by pressing the roll of web 6, also causes the web to roll tightly about the spindle 18, and moreover prevents accidental unwinding.

When the web 6 on the spool is to be 55 moved, the latches 22 are thrown to inoperative positions, to release the spool to permit it to be dismounted from the bracket arms 15, after which one of the heads 20 (mounted on one end of the spindle and normally confined between a shoulder 35 on the spindle and one of the bracket arms 15) is removed, to enable the roll of printed web to be drawn endwise from the spindle. The leading end of the web slides from beneath 60 the free end of the clamping finger 25 with-

out mutilation. The clamping finger protrudes from the spindle, and in order to avoid uneven winding of the web 6 on the spool, the hub 36 of the removable head 20 (said hub having the same circumference as the spindle and fitting on the reduced end 40 thereof), has a rib or support 37 projecting beyond its circumference to a height equal to that of the clamping finger 25, the web being wide enough to bridge the gap, 70 and rest upon both the clamping finger and the rib. The spindle 18 has a tooth 39 projecting from the shoulder 35 to fit in a recess 38 in the hub 36 (Fig. 6) to prevent relative rotation of the head 20 and the spindle, 75 and also to insure that, in assembling the 80 spool, the rib shall lie in line with the clamping finger 25.

The spool is preferably located between the guide and the platen, and the web is led beneath the guide to enable the bight 17 to fall loosely and accumulate in a pile as it is fed from the platen, so that it will not 85 interfere with the operator, who may continue writing until the rolls 1, 2, are nearly exhausted before winding the printed record 90 on the spool. The platen is drawn forward in letter feeding direction by means of a spring barrel 41 and is controlled in said feeding by an escapement wheel 42 connected to a ratchet 43 working in a rack 44 on the platen carriage; said wheel controlled 95 by dogs 45 which in turn are operated by the usual universal bar 46 of the Underwood typewriting machine.

Variations may be resorted to within the 100 scope of the invention, and portions of the improvements may be used without others.

Having thus described my invention, I 105 claim:

1. The combination with the traveling platen of a typewriting machine, of a web-coiling mechanism back of the platen and including a rotatable spool, and a web guide through which the web is led prior to coiling 110 on the spool, said guide located on that side of the spool farthest from the platen to permit a bight of the web to form below the spool, to avoid straining the web during the 115 travel of the platen; said guide being swiveled and having a part to run upon the roll, to control the position of the guide.

2. The combination with the traveling platen of a typewriting machine, of a fixed 120 web-coiling mechanism including a spool, relatively to which the platen travels, said web-coiling means located apart from the platen, an incline in rear of the platen down over which the reach of web between the 125 platen and web-coiling device is led, and a support above the surface of said incline to hold the web off from said incline, to reduce the area of frictional contact and strain on the web as it swings edgewise to and fro on 130

the incline to accommodate the movement of the platen.

3. The combination with the traveling platen of a typewriting machine, of a fixed web-coiling mechanism including a spool, relatively to which the platen travels, said web-coiling means located apart from the platen, an incline in rear of the platen down over which the reach of web between the platen and web-coiling device is led, a support above the surface of said incline to hold the web off from said incline, to reduce the area of frictional contact and strain on the web as it swings edgewise to and fro on the incline to accommodate the movement of the platen, and a web-confining bar overlying said support.

4. The combination with the traveling platen of a typewriting machine, of a support, a web-coiling spool journaled in the support 20 and to which the web is led, a catch to releasably fasten the web to the spool, a combined edge guide and brake along which a free bight of the web is led prior to coiling 25 on the spool, and releasable means to hold the spool in place on its support.

5. The combination with the traveling platen of a typewriting machine, of a web-coiling mechanism stationary with respect to the traveling movement of the platen, and 30 including a rotatable spool, a swinging edge guide for the web through which the web is led prior to coiling it on the spool, and a follower extending from the guide to press 35 against the coils on the spool, and effective to adjust the guide so that the web is fed directly to the circumference of the roll as it varies in diameter.

6. The combination with the traveling 40 platen of a typewriting machine, of a web-coiling mechanism stationary with respect to the traveling movement of the platen, and including a rotatable spool, a swinging edge guide for the web through which the web is led prior to coiling it on the spool, a spring 45 tending to rock the guide in one direction, and a follower extending from the guide to press against the coils on the spool, and effective to adjust the guide so that the web 50 is fed directly to the circumference of the roll as it varies in diameter.

7. The combination with the traveling platen of a typewriting machine, of a web-coiling mechanism stationary with respect to the traveling movement of the platen, and 55 including a rotatable spool, a swiveled guide comprising a plate having ways formed along its side edges through which the web passes on its way to the spool, a follower 60 formed as an extension of said plate, and means holding said follower against the coiled web on the spool.

8. The combination with the traveling platen of a typewriting machine, of a web- 65 coiling mechanism stationary with respect to

the traveling movement of the platen, and including a rotatable spool, a flat surface on which said web may lie intermediate said platen and spool, and a rod holding the sliding web clear of part of said surface.

70

9. The combination with the traveling platen of a typewriting machine, of a web-coiling mechanism stationary with respect to the traveling movement of the platen, and including a rotatable spool, a guide intermediate said platen and spool, over which said web may hang loosely, a swinging plate over which said web is led to said spool, and marginal guides on said plate comprising overhanging portions under which said web 80 is led.

75

10. The combination with the traveling platen of a typewriting machine, of a web-coiling mechanism stationary with respect to the traveling movement of the platen, and including a rotatable spool, a guide intermediate said platen and spool, over which said web may hang loosely, a swinging plate over which said web is led, marginal guides 85 on said plate comprising flaring portions, 90 and overhanging guides into which said flaring portions turn.

85

11. In a typewriting machine, the combination with a traveling platen, of a spool stationary with respect to the traveling movement of the platen and on which a web may be wound as it is led from said platen, means for supporting a loose bight of web between said platen and said spool, a plate comprising edge guides over which 95 said web is drawn to said spool, and an extension of said plate forming a brake adapted to bear against the web on said spool.

95

12. In a typewriting machine, the combination with a traveling platen, of a spool 105 stationary with respect to the traveling movement of the platen and on which a web may be wound as it is drawn from said platen, a swinging guide plate comprising edge guides closely fitting said web to guide said web squarely to said spool, a table much wider than said spool over which a long loose bight of said web may lie, and a rod holding said web clear of part of said table.

110

13. In a typewriting machine, the combination with a traveling platen, of a spool stationary with respect to the traveling movement of the platen and on which a web may be drawn from said platen, and guides having flaring ends adapted to engage the 120 side margins of said web and guide it squarely onto said spool.

115

14. In a typewriting machine, the combination with a traveling platen, of a web-coiling mechanism stationary with respect to 125 the traveling movement of the platen and including a rotatable spool or reel, a yielding brake pressing against the web as it is coiled on the spool to insure a snug winding thereof, and paper-guiding means on said brake. 130

15. In a typewriting machine, the combination with a traveling platen, of a web spool stationary with respect to the traveling movement of the platen and from which a web may be drawn around the platen to a stationary receiving spool mounted on the casing containing said first spool, and edge

guides for guiding a loose bight of said web onto said second spool from the cover of said casing.
